(57) **CLAIM**

The ornamental design for a passenger seat with grab rail, as shown and described.

DESCRIPTION

FIG. 1 is a front elevation view of a passenger seat with grab rail showing my new design.

FIG. 2 is a top plan view thereof.

FIG. 3 is a rear elevation thereof.

FIG. 4 is a bottom plan view thereof.

FIG. 5 is a right side elevation view thereof. The left side elevation is a mirror image of FIG. 5; and,

FIG. 6 is a perspective thereof.
